Primary Examiner — Jae Liang*Assistant Examiner* — Christopher Torma(74) *Attorney, Agent, or Firm* — Andrew C. Cheng(57) **CLAIM**

The ornamental design for a TV cabinet as shown and described.

DESCRIPTION

FIG. 1 is a top, front and right perspective view of a TV cabinet showing our new design;

FIG. 2 is a bottom, rear and left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of encircled portion 9 of FIG. 1. The dash-dash broken lines depict portions of the TV cabinet that form no part of the claimed design.

The dot-dash broken line portion of the figure drawings is included to show boundaries of enlarged views that form no part of the claimed design.

1 Claim, 9 Drawing Sheets(56)
